The ornamental design for a tile edging strip, as shown and described.

DESCRIPTION

FIG. 1 is a perspective view from one end of the tile edging strip which is broken in the center to indicate indeterminate length, and the pattern of the openings and the grooves is repeated throughout the width thereof; and,

FIG. 2 is an enlarged view of the other end.

The configurations of the flange and the groove located on the bottom left end of the tile edging strip in FIG. 1, are continuous throughout the width thereof.
